co, Inc., Perrysburg, Ohio, a corporation of
Ohio

Application July 11, 1938, Serial No. 218,583

4 Claims. (Cl. 40—132)

This invention relates to attractive portable displays effective whether or not illuminated.

This invention has utility when incorporated in collapsible shadow box frames, even enclosed and 5 metallic against fire hazard.

Referring to the drawing:

Fig. 1 is a front elevation of an embodiment of the invention in the portable sign hereunder;

Fig. 2 is an end elevation from the right of the 10 sign of Fig. 1;

Fig. 3 is a distributed view of the sign of Fig. 1 with the insert display as partially in position and the closure frame section therefor;

Fig. 4 is a section on the line IV—IV, Fig. 1, 15 showing the light in enclosed position in the assembly;

Fig. 5 is a view of the collapsed wings as to the frame from the rear;

Fig. 6 is a section on the line VI—VI, Fig. 4, 20 showing the interlock for cooperation between the free ends of the wings from the frame; and

Fig. 7 is an elevation of the back closure or cap to complete the shadow box.

Electric conductors 1, 2, in conduit 3 lead to 5 fixture 4 having insulation rings 5 at mounting opening 6 in back 7 for the electric incandescent light 8. This back 7 is shown as having marginal flanges 9, 10, coacting with free ends of the wings 11, 12, 13, 14. Each of these wings has on the 30 fourth edge an aligned series of ventilation openings 15 with spacing 16 therebetween as an effective hinge located by these openings.

Integral with the wings 11, 12, is frame side 17 having front frame stiffening portion 18 there- 35 along and spot welded therewith. Wings 13, 14, have integral extensions 19 forming a front of connecting frame piece with back stiffening portion 20 between the wing portions 17. There is a substantial rectangular frame having opening 21. 40 This frame base is bounded on three sides by trim 22 having an inwardly directed flange 23. Opposed thereto is flange 24 weld anchored with the back of the frame proper. Between the flange 23 and the main frame is a clearance in which may 45 be inserted display panel 25, say of glass having selected indicia or advertising 26. As such transparency or partial transparency or translucency be thrust into position, the supplemental frame side 27 (Fig. 5) may be slipped into cooperation 50 with springs tongues 28 in completing the trim for the display. These tongues or lugs 28 are spot welded with the frame side 20 to overhang the side 27. The sign is accordingly one in which the substitutive disclosures may be readily inserted 55 and replaced independently of any change in the set-up or light position, whether the light be out, continuous or flashing.

An advantage hereunder has to do with the compact shape in which this device, say as made 60 of sheet metal, may be placed for shipment, for

in such circumstances the hinge means 16 allow the several wings to be collapsed or lie flat against the main frame. For setting up, it is in order to spread the wings 11, 12, into approximate parallelism away from the frame. The sides 13, 14, are 5 brought out but still have a converging direction, and arc shaped offsets 29 from these converging sides 13, 14 (Fig. 6), adjacent the free end cooperate with complementary arc-shaped offsets 30 in the wings 11, 12. There is thus an effective 10 and stiff interlocking of this sheet metal fireproof set-up. As this snug form is provided, the back 7 may be snapped into position to close this portion between the wings, to which end the flanges 9 snugly rest against the free ends of the sides 15 13, 14. Flanges 10 have arc-shaped offsets 31 co-acting with complementary arc-shaped flange offsets 32 of the wings 11, 12, and this snapping of the back 7 is accordingly in a snug holding position against casual shifting. This means that 20 there is a substantial set-up of fire safety provision.

What is claimed and it is desired to secure by Letters Patent is:

1. For a translucency, a frame, a pair of wings 25 converging therefrom, an additional pair of wings spaced by the converging wings, each of said wings being integral with a side of the frame, and a separate back providing a mounting for a light to be directed toward the frame, there being 30 flanged holding means between the edges of the back and the edges of the wings forming a nested assembly.

2. For a translucency, a frame, a pair of wings 35 converging therefrom, an additional pair of wings spaced by the converging wings, each of said wings being integral with a side of the frame, and therealong having a series of ventilation openings with spaced hinge-providing portions therebetween, and a peripherally inwardly flanged back 40 interengaging with such wings remote from the frame.

3. For a translucency, a frame, a pair of wings converging therefrom, an additional pair of wings spaced by and forming angles in extending from 45 the converging wings, each of said wings being integral with a side of the frame, there being nested arc stops abutting said angle to register the converging wings with the additional pair of wings.

4. For a translucency, a frame, a pair of wings converging therefrom, an additional pair of wings spaced by the converging wings, each of said wings being integral with a side of the frame, and a peripheral flange-carrying back having offset 55 arc stops to interfit with complementary stops on the free ends of the wings with which the back is snapped into assembly as a cap.
